UNITED STATES PATENT OFFICE.

SETH WILLIAM BABBITT, OF MERIDEN, CONNECTICUT.

DESIGN FOR SILVERSMITHS' STOCK.

SPECIFICATION forming part of Design No. 27,587, dated August 31, 1897.

Application filed July 22, 1897. Serial No. 645,598. Term of patent 7 years.

To all whom it may concern:

Be it known that I, SETH WILLIAM BABBITT, a citizen of the United States, residing at Meriden, in the county of New Haven and State of Connecticut, have invented and produced a new and original Design for Silversmiths' and Britannia-Workers' Stock; and I do hereby declare the following to be a full, clear, and exact description of the same, reference being had to the accompanying drawing, forming a part thereof.

This invention relates to a new and original design for silversmiths' and britannia-workers' stock, and is embodied in the design shown in the accompanying drawing and hereinafter described.

This invention relates more particularly to that class of material or stock used in connection with the decoration of silver and britannia hollow and flat ware, and the especial design illustrated consists of a spray of flowers and leaves.

The end A consists of stems arranged at an

incline, while the central portion B is composed principally of flowers in clusters and arranged in substantially a horizontal line, terminating at the opposite end in a spray C, which is arranged at an incline or oblique.

While I have shown and described the opposite ends as arranged at an incline, it is to be understood that they can be otherwise arranged without departing from the invention, the essential feature of which is the general arrangement of the flowers and leaves.

Having thus described the invention, what is claimed as new, and desired to be secured by Design Letters Patent, is—

The design for silversmiths' and britannia-workers' stock, substantially as shown and described.

In testimony whereof I affix my signature in presence of two witnesses.

SETH WILLIAM BABBITT.
